(57) **CLAIM**

The ornamental design for a chair, as shown and described.

DESCRIPTION

FIG. 1 is a front perspective view of a chair according to a first embodiment.

FIG. 2 is a front view of the chair of FIG. 1.

FIG. 3 is a rear view of the chair of FIG. 1.

FIG. 4 is a left-side view of the chair of FIG. 1.

FIG. 5 is a right-side view of the chair of FIG. 1.

FIG. 6 is a top view of the chair of FIG. 1.

FIG. 7 is a bottom view of the chair of FIG. 1.

FIG. 8 is a front perspective view showing the chair of FIG. 1 in an environment that includes a stand for supporting the chair in a hanging position and showing a cushion on a seating surface of the chair.

FIG. 9 is a front perspective view of a chair with legs according to a second embodiment.

FIG. 10 is a front view of the chair of FIG. 9.

FIG. 11 is a rear view of the chair of FIG. 9.

FIG. 12 is a left-side view of the chair of FIG. 9.

FIG. 13 is a right-side view of the chair of FIG. 9.

FIG. 14 is a top view of the chair of FIG. 9.

FIG. 15 is a bottom view of the chair of FIG. 9; and,

FIG. 16 is a front perspective view of the chair of FIG. 9 showing a cushion on a seating surface of the chair.

In the drawings, the ornamental design that is claimed is shown in solid lines. The broken lines shown in the drawings are for the purpose of illustrating environmental subject matter and form no part of the claimed design.

1 Claim, 16 Drawing Sheets
